Fig. 2

To all whom it may concern:

Be it known that I, Earl H. Weller, a citizen of the United States and a resident of Bay Village, county of Cuyahoga, State of Ohio, have invented a new, original, and ornamental Design for a Wheeled Power-Driven Sprayer and Mister, of which the following is a specification, reference being had to the accompanying drawings, forming a part thereof, wherein:

Figure 1 is a front perspective view of a wheeled power-driven sprayer and mister showing my new design;

Figures 2 and 3 are opposite side elevational views thereof; and

Figure 4 is a rear elevational view thereof.

The dominant features of my design reside in the parts shown in solid lines.

I claim:

The ornamental design for a wheeled power-driven sprayer and mister, as shown and described.
